US00D690027S

(12) **United States Design Patent**
Motadel

(10) **Patent No.:** **US D690,027 S**
(45) **Date of Patent:** **** Sep. 17, 2013**

(54) **PIPETTE TIP HANDLING DEVICE**

(71) Applicant: **Biotix, Inc.**, San Diego, CA (US)

(72) Inventor: **Arta Motadel**, San Diego, CA (US)

(73) Assignee: **Biotix, Inc.**, San Diego, CA (US)

(**) Term: **14 Years**

(21) Appl. No.: **29/437,631**

(22) Filed: **Nov. 19, 2012**

Related U.S. Application Data

(63) Continuation-in-part of application No. 29/345,142, filed on Oct. 9, 2009, now Pat. No. Des. 673,295, which is a continuation-in-part of application No. 12/422,250, filed on Apr. 11, 2009, and a continuation-in-part of application No. 29/335,253, filed on Apr. 11, 2009.
